UNITED STATES PATENT OFFICE.

WILLIAM T. SHANNON, OF CINCINNATI, OHIO.

METAL CULVERT.

1,040,442.

Specification of Letters Patent.

Patented Oct. 8, 1912.

Application filed July 19, 1912. Serial No. 710,347.

To all whom it may concern:

Be it known that I, WILLIAM T. SHANNON, a citizen of the United States of America, and resident of Cincinnati, county of 5 Hamilton, and State of Ohio, have invented certain new and useful Improvements in Metal Culverts, of which the following is a specification.

My invention relates to metal culverts 10 which are composed of sheet metal sections. Some of the objections to which culverts of this character have been open are that means have not been provided for securing the sheet metal sections one to another quickly 15 and in a manner such that the locking means would not be rusted out by the action of the moisture.

The object of my invention is a culvert provided with a means for readily securing 20 the sections together, which not only does not weaken the sections and render them pervious to rust, but strengthens them.

A metal culvert embodying my invention 25 is illustrated in the accompanying drawings, in which—

Figure 1 is a perspective view of the bottom plates of two sections of a culvert embodying my invention. Fig. 2 is a similar view, but with the arched cover plates in 30 position upon the bottom plates. Fig. 3 is a sectional view taken upon line 3—3 of Fig. 2. Fig. 4 is a longitudinal sectional view taken upon line 4—4 of Fig. 2.

Each section of the culvert consists of a 35 bottom plate A and an arched cover plate B. The bottom plates have adjacent to each edge trough shaped grooves a a', of a width approximately equal to the thickness of the corrugated cover plates. Each of the trough 40 shaped grooves a a' terminates in a down-turned flange a², a³. The trough shaped groove and the down-turned flange upon each edge of a bottom plate, form an ogee curve along each edge of said plate. The 45 arched cover plates are of a span equal to the distance between the grooves in the bottom plates. Preferably the arched plates are corrugated to give them rigidity.

In assembling the parts to form a culvert the bottom plates A are locked one to another by placing them end to end and forcing the ogee curves of one plate into the ogee curves of an adjacent plate, as shown in Figs. 1 and 4. The arched plates are then engaged with the bottom plates by forcing 55 their ends into the trough shaped grooves in the bottom plates. When the arched plates are so positioned upon the bottom plates, a pressure, downward upon the cover plates, such as is exerted by earth placed 60 upon the cover plates, tends to spread the cover plates, and to place the bottom plates under tension. This because of the ogee character of the flanges on the bottom plates, puts the bottom plates under tension, and 65 thus firmly closes the joints between adjacent plates of the bottom. The trough shaped groove and the down-turned flange upon each edge of a bottom plate stiffens the edges of the plate and affords an efficient resistance to the outward pressure 70 upon the edges of the cover plates. The bottom plates being secured together by an integral locking means avoids the use of rivets with the consequent punching of the 75 plates, and hence there is no metal which is left uncoated. Therefore there is no part of the metal sections which are liable to become rusted. The cover plates are locked together 80 at their ends by the interlapping of the corrugations, as shown in Fig. 4.

What I claim is:

A culvert composed of sheet metal sections, each section consisting of an arched upper plate and a flat bottom plate, each 85 bottom plate having near each edge a trough shaped groove with its outer wall terminating in a down-turned flange, said grooves and flanges of adjacent bottom sections being fitted into one another to lock said bottom plates together, and the arched plates being seated in the grooves.

WILLIAM T. SHANNON.
